US0D1102460S

(12) **United States Design Patent** (10) **Patent No.:** **US D1,102,460 S**
(45) **Date of Patent:** **** Nov. 18, 2025**

(54) **DISPLAY SCREEN OR PORTION THEREOF
WITH GRAPHICAL USER INTERFACE**

(71) Applicant: **Abbott Diabetes Care Inc.**, Alameda, CA (US)

(72) Inventors: **Prashanth Chodagiri**, San Francisco, CA (US); **Panganamala Ashwin Kumar**, Oakland, CA (US); **Jennifer Revolter**, Burien, WA (US); **Jonathon Wood**, Seattle, WA (US); **Sabine Kabel-Eckes**, Mountain View, CA (US); **Vyshnnavi Parthasarathy**, Fremont, CA (US); **Cynthia Poulton**, Berkeley, CA (US); **Jeffrey Nishida-Boucher**, Redwood City, CA (US); **Gary Hayter**, Oakland, CA (US)

(73) Assignee: **Abbott Diabetes Care Inc.**, Alameda, CA (US)

(**) Term: **15 Years**

(21) Appl. No.: **29/951,374**

(22) Filed: **Jul. 9, 2024**

CLAIM

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
